UNITED STATES PATENT OFFICE.

WILSON G. ROSS AND JOHN J. REID, OF BENICIA, CALIFORNIA.

CRIBBAGE-BOARD.

SPECIFICATION forming part of Letters Patent No. 614,028, dated November 8, 1898.

Application filed December 31, 1897. Serial No. 664,847. (No model.)

To all whom it may concern:

Be it known that we, WILSON G. ROSS and JOHN J. REID, of Benicia, in the county of Solano and State of California, have invented 5 a new and Improved Cribbage-Board, of which the following is a full, clear, and exact description.

This invention relates to counting-boards especially used in counting the game of cribbage; and the object is to provide a board of this character with which the use of pins as ordinarily employed is dispensed with, thus obviating the danger of loss of the counting devices.

15 We will describe a cribbage-board embodying our invention and then point out the novel features in the appended claims.

Reference is to be had to the accompanying drawings, forming a part of this specification, 20 in which similar characters of reference indicate corresponding parts in all the figures.

Figure 1 is a top plan view of a cribbage-board embodying our invention. Fig. 2 is a section on the line 2 2 of Fig. 1, and Fig. 3 25 is a section on the line 3 3 of Fig. 1.

The cribbage-board comprises a frame or casing 1 of any suitable material and in which is arranged a number of rods 2, here shown as rectangular in cross-section. These 30 rods 2 have trunnion-bearings in the end walls of the frame 1, so that they may be axially rocked. Each rod 2 is provided on one side with a series of numbers 3, running consecutively from "1" to "30," and on the next 35 surface, at right angles to the surface having said numbers, is a series of numbers 4, reading consecutively from "31" to "60." Three of the edges of each rod 2 are provided with notches 5, the said notches being directly 40 opposite the figures marked on the rod.

Extended longitudinally of the frame 1, at each side of a rod 2, is a guide-rod 6, and mounted to slide on each guide-rod 6 is a loop 7, from which a finger-piece 8 extends upward. The finger-piece 8 is projected toward the rod 2 and is designed to be engaged with either one of the notches 5.

The end of each rod 2 is provided with a finger-piece 9, by means of which the rod may 50 be rocked. The rods are held yieldingly in position by means of springs 10, here shown as bearing at their central portions against the bottom of the frame 1 and engaging with their ends bars 11, upon the upper surfaces 55 of which the rods 2 engage.

In using the device at the commencement of a game the surfaces of the bars having the numbers from "1" to "30" will of course be upward. Then as counts are made the counters 8 may be lifted up relatively to the guide- 60 rods 6 and slid along until the proper number of the count is reached. Then the finger-piece 8 will be dropped into the notches 5. After the number "30" shall have been reached and another count is made the bar 65 2 must be rocked or given a one-fourth rotation to bring the higher numbers upward. Then the count will proceed as before.

Having thus described our invention, we claim as new and desire to secure by Letters 70 Patent—

1. A cribbage-board, comprising a frame, a bar mounted to rotate or rock therein, the said bar having numerals on two of its surfaces, guide-rods in the frame, and counters 75 movable longitudinally of said guide-rods, substantially as specified.

2. A cribbage-board, comprising a frame, a bar mounted to rock therein and having numerals on two of its surfaces, and also having notches in its edges, guide-rods extended along the sides of the bar, loops engaging around said guide-rods, and finger-pieces on the loops adapted to engage in either one of the notches of the bar, substantially as 80 85 specified.

3. A cribbage-board, comprising a frame, a number of bars having trunnion-bearings in said frame, each bar being rectangular in cross-section, and having numerals on two of 90 its surfaces, and also having notches in its edges, guide-rods extended along the two sides of each bar, loops engaging around said guide-rods, and finger-pieces on said loops adapted to be moved into the notches of the 95 bars, substantially as specified.

4. A cribbage-board, comprising a frame, a bar rectangular in cross-section mounted to rock in said frame, the said bar being provided on two of its surfaces with numerals 100 and having notches in its edges, counters movable along said bar, and a spring or springs for holding said bar yieldingly in position.
